UNITED STATES PATENT OFFICE.

HARVEY SEWARD, OF PETERSBURG, VIRGINIA.

TRAY-HANDLE.

No. 908,042.

Specification of Letters Patent.

Patented Dec. 29, 1908.

Application filed July 20, 1908. Serial No. 444,425.

To all whom it may concern:

Be it known that I, HARVEY SEWARD, citizen of the United States, residing at Petersburg, county of Dinwiddie, and State of Virginia, have invented certain new and useful improvements in Tray-Handles, of which the following is a specification, reference being had therein to the accompanying drawing.

This invention relates to a tray handle, 10 and particularly to a construction adapted to lie flush with the upper surface of the trunk tray and to embrace the sides thereof.

The invention has for an object to form a handle from a single blank having a tubular central portion disposed in alignment with a proper recess in the trunk tray wall, while the opposite ends thereof are disposed in parallel planes to embrace a wall of the tray and thus resist lateral strain while providing 20 the necessary rigidity in the intermediate portion of the handle.

Other and further objects and advantages of the invention will be hereinafter fully set forth and the novel features thereof defined 25 by the appended claims.

In the drawing:—Figure 1 is a perspective of the invention applied; Fig. 2 is a detail perspective thereof showing the under side; Fig. 3 is a section on line 3—3, Fig. 1; Fig. 4 30 is a section on line 4—4, Fig. 1, and Fig. 5 is a plan of the blank from which the handle is formed.

Like numerals refer to like parts in the several views of the drawing.

35 The numeral 10 indicates a blank of suitable material, preferably sheet metal, which is provided at opposite ends with suitable apertures 11 centrally disposed therein to receive the securing devices 12, as shown in Fig. 1.

40 The side edges 13 of this blank are bent intermediate of the ends to form a tubular portion 14, as shown in Fig. 2, while at the free ends of the handle the side edges 13 are disposed in parallel planes separated from 45 each other as shown at 15 so as to embrace the wall 16 of the tray or other object to which the handle is applied. This wall is provided with the recess or cutaway portion 17 in alignment with the tubular portion 14

50 of the handle. The tubular portion is merged into the flanged portion by the curved face 18. This handle is adapted to be

applied to a trunk tray or any other desired receptacle where it is essential that the upper surface thereof be substantially flush 55 with the top of the receptacle or disposed in a straight line, and the construction here shown provides for a tubular hand hold which not only affords a convenient grip but also stiffens and braces this portion to prevent bending thereof when made of light sheet metal which is liable to occur if the receptacle is weighted. The parallel end flanges 15 by embracing the opposite sides of the wall to which they are applied resist 60 any lateral strain and thereby reduce the strain upon the holding devices passing through the upper surface of the handle. The invention therefore presents a simple, efficient and economically constructed form 70 of handle adapted to be formed from a single blank and to be readily bent into the form shown which provides rigidity of the handle and means for securely attaching it to the receptacle upon which it is applied. 75

Having described my invention and set forth its merits what I claim and desire to secure by Letters Patent is:—

1. A tray handle comprising a plate having a straight upper face and the side edges at 80 its opposite end portions bent at an angle thereto and extended parallel to and separated from each other, and its intermediate portion formed of tubular cross section.

2. A tray handle comprising a plate having its side edges in contact to form a tubular portion intermediate of its ends and said ends bent at an angle to the body of the plate and parallel to each other to form embracing flanges thereon. 90

3. A tray handle comprising a plate having its side edges intermediate of the ends in contact with each other to form a transversely elongated tubular portion, and merging into parallel angularly disposed flanges 95 separated from each other and extended laterally from each end of the intermediate tubular portion of the plate.

In testimony whereof I affix my signature in presence of two witnesses.

HARVEY SEWARD.
